BLASTING INITIATOR LOADING MACHINE

Charles Russell Johnson, Glenn Mills, Pa., and Edgar H. Schmidt, Wilmington, Del., assignors to E. I. du Pont de Nemours & Company, Wilmington, Del., a corporation of Delaware

Application May 7, 1952, Serial No. 286,532

5 Claims. (Cl. 86—1)

1

The present invention relates to a novel machine for loading accurately measured charges of explosive material into blasting initiator shells having a minimum amount of moving parts and possessing a high degree of safety.

Millions of blasting initiators are manufactured annually for various industrial users, and include such items as electric squibs and electric blasting caps, delay igniters, and blasting caps adapted to be fired by fuse. A basic component in each of the blasting initiators is a highly sensitive explosive composition, usually in the form of a powder. To insure uniformity and dependability, it is essential that the quantity of this basic component be identical in each initiator of a selected type. Due to the sensitivity of the composition, one of the most hazardous steps in the manufacture of explosive devices is the step of measuring and loading a predetermined amount of the ignition material into an initiator shell. While the quantity desired in each initiator is relatively small, accurate control of the measuring and of the insertion into the shell must be maintained with a minimum amount of human manipulation so as to reduce the hazard to personnel.

It has become the practice in the initiator manufacturing art to use apparatus adapted to be remotely controlled by an operator behind a barricade for this loading operation, and a number of such devices are well known. While the performance of the abovementioned machines is, in most cases, satisfactory for the conditions for which they are designed, they have not fully met the need of the industry for a loading machine having the high safety characteristic and accurate regulation of the charge and which is also adapted to load a large number of initiator shells automatically and with a minimum amount of operator manipulation. In addition, most of the prior art machines can not be adjusted to permit changes in the measurement of material and height of the initiator shell, and the cleaning of the machine continues to be a dangerous task.

It is an object of the present invention to provide a loading machine for blasting initiators which is adapted to accurately measure and load explosive charges automatically into blasting initiator shells. A further object is to provide such machine wherein a minimum amount of operator supervision is required. A still further object is to provide such machine wherein parts are readily interchangeable for adjustment in the charge measurement. An additional object is to provide a loading machine wherein cleaning is simplified and rendered non-hazardous. Addi-

2

tional objects will become apparent as the invention is further described.

We have found that the foregoing objects may be attained when we provide a measuring plate 5 containing a plurality of holes of equal volume extending the thickness of the plate, a means for temporarily closing the bottom ends of the holes, means for distributing explosive composition into and uniformly filling said holes, and a means for 10 thereafter opening the bottom ends of the holes and directing the flow of explosive composition into initiator shells. In addition to the above, we desirably provide a means for locking all elements into the closed position, and inverting the plate for cleaning purposes.

The present invention will be more fully understood by reference to the accompanying drawings which illustrate a specific embodiment of the invention. It will be understood that the invention is not to be considered as limited to the embodiment shown in the drawings.

In the drawings:

Figure 1 represents a front view and Figure 2 represents a top view of a complete machine embodying the features of the present invention;

Figure 3 represents a detail view of the hopper and measuring plate assembly;

Figure 4 represents a detail view of the measuring plate and sealing and nozzle plate construction;

Figures 5 and 6 represent enlarged views of the sealing element;

Figures 7, 8 and 9 represent views of the paddle and paddle drive mechanism; and

Figure 10 represents a side view of the mechanism illustrating the locking and dumping assembly.

Referring to the figures in greater detail, 1 is a tub shaped hopper mounted on a base plate 2. 40 Mounted on the base plate 2 are support bearings 5, 6, and 7, the latter two being connected to each other by the strengthening rib 8. Shaft 9 passes through bearings 5 and 6, thereby supporting base plate 2, and is in turn supported by the terminal bearing 10 and housing 11, the bearing 10 and the housing 11 being mounted on the main framework 12. The framework 12 rests on the supporting surface of floor and consists of structural steel beams welded or riveted in the desired arrangement.

The base plate 2 is additionally supported by the pins 13 extending from the framework 12 and nesting in the guide plates 14. A vibrator 15 is mounted on the base plate 2 adjacent to the hopper 1.

Centrally positioned within the hopper 1 and supported by the base plate 2 is the measuring plate 17 containing openings 36. Suspended below plate 17 is the nozzle plate 40 containing downwardly projecting nozzles 16 and upwardly projecting resilient sealing elements 38. The plate 40 is suspended on four rack-pins 41 which extend within the housings 18 and 19 mounted on base plate 2 at the front and rear of the hopper 1 and are in engagement with teeth 42 cut into shafts 9 and 20, shaft 9 passing through housing 18, and shaft 20 passing through housing 19. Shafts 9 and 20 are interconnected by means of yoke 21. A flexible sheathing 43 around each pin 41 prevents powder from gathering around the pins 41. The sealing elements 38 contain openings 39 in the stem to permit the passage of powder.

Beneath base plate 2 is shelf 24, the central portion 25 being designed to position a block of initiator shells directly under the nozzles 16. The paddle blades 51 and 52 are supported inside the hopper 1 by the paddle shaft 29, which in turn is supported in crosshead 27 suspended on guide rods 26. Paddle blade 52 contains a triangular strip 53 on the bottom, this strip being of resilient material and adapted to wipe the surface of the measuring plate 17. The crosshead 27 contains the rack-bar 44 guided by extension 45 within the drilled guide passage 46. Cam roller 47 is fastened to rack-bar 44 and operates in cam track 48 of cam 31. Cam roller 49 is fastened directly to crosshead 27, and operates in cam track 50 of cam 32. The cams 31 and 32 are slidably mounted on shaft 30 containing feather key 28. Mounted on the framework 12 are the cam rollers 58 and 59, in engagement with cam tracks 48 and 50, respectively.

Adjacent to the housing 11 is the dump mechanism housing 22 which surrounds shaft 9 and contains a rack-bar 4 in engagement with gear 54, mounted on the housing of support bearing 6. Rack-bar 4 is actuated by hydraulic unit 23. The housing 11 contains cam track 57 which guides cam roller 56 mounted on yoke 21. Yoke 21, when the hopper 1 is in normal position, is in engagement with operating pin 55.

The hopper 1 in this particular construction contains a powder shelf 3 completely around the periphery, and is made in two sections which are joined together by rivets 33 in flanges 34.

The operation of the loading machine of the present invention is as follows: A quantity of ignition composition is dumped, either mechanically or by an operator, into the powder hopper 1. A block of empty initiator shells is fed into space 25 of shelf 24, and locked into position so that the open ends of the shells are directly under the nozzles 16. This operation may be performed either automatically or as an individual operation.

The shaft 30 is now slowly rotated (the drive mechanism not being shown) in the direction indicated in Figure 7. Due to the contour of track 48, the cam roller 47 is moved toward the right, and cam 31 also moves to the right, this latter motion being produced by the action of cam roller 58 in cam track 48. During the first 90 degrees of rotation of shaft 30, the cam 32 maintains its relative position on shaft 30, and the crosshead 27 remains stationary. Thus rack 44 moves to the right within crosshead 27, rotating paddle shaft 29 90 degrees, and moving paddle blade 51 downward into the hopper, pushing powder ahead of it. Further rotation of shaft 30

produces a movement to the right of cams 31 and 32, and of crosshead 27, the shaft 29 being carried to the right without further rotation. Paddle blade 51 thus distributes a uniform layer of powder over measuring plate 17. When the crosshead 27 is in its extreme righthand position (180 degrees rotation of shaft 30), further rotation of shaft 30 moves cam 31 towards the left and cam roller 47 is also moved to the left, while the crosshead and cam 32 remain at the righthand position. This motion reverses the rotation of paddle shaft 29, thus restoring it to the original position, i. e., blade 52 downward into the hopper.

During this rotation of the paddle shaft 29, the compressed air vibrator 15 is actuated. The vibrator 15 imparts sufficient vibration to the base-plate 2 to cause the loose powder over measuring plate 17 to fill completely the holes 36, the nozzle plate 40 being in the raised position.

The remaining 90 degrees rotation of shaft 30 moves the crosshead 27 to the left without further rotation of the paddle shaft 29, thus drawing paddle blade 52 over the measuring plate 17. The strip 53 of resilient material fastened to the bottom of blade 52 wipes the surface of measuring plate 17 free of powder without disturbing the powder in holes 36, and piles the excess powder on the lefthand side of hopper 1. This completes one cycle of the paddle assembly operation, and, after a short pause, the second cycle is commenced. During the period that the paddle is stationary, operating pin 55 is moved by mechanism not shown, towards the paddle assembly side of the apparatus, thereby moving the yoke 21, and rotating shafts 9 and 20. This rotation lowers the pins 44, dropping nozzle plate 40 towards the initiator shells, and releasing the sealing elements 38 from contact with openings 36. Vibrator 15 is again actuated, and the powder in the openings 36 drops through the openings 39 in the stems of the sealing members 38 and out of the nozzles 16 into the initiator shells. The pin 55 is then reciprocated to its original position, returning the yoke 21, and thereby raising the nozzle plate 40 so that the sealing members 38 again close the bottoms of the openings 36. The initiator shell block is now removed and replaced with a block containing empty shells, and the entire operating cycle resumed.

It will be understood, of course, that the sequence of operation described above is synchronized by conventional means, and that an initial supply of powder in the hopper 1 will provide enough bulk material for from twenty to seventy cycles of loading before a new supply is required. The mechanism may be actuated by any conventional motive means, such as an electric motor, and, may, if desired, be so geared that a single source of power will provide all of the motive power. The type of motor and the mechanism used to produce the desired movements of the various elements, i. e., the cam shaft 30, the vibrator 15, and the operating pin 55, are not a part of the present invention, and are, accordingly, not illustrated or described herein.

The present mechanism is adapted to be operated either as an individual unit, or as part of a general initiator assembly line. If used in combination with other operating units, the speed of operation will, of course, be regulated to meet the requirements of the line. For example, using the described apparatus, 5000 initiators have been loaded in one hour, without experiencing any difficulty. The drawing illustrates a nozzle plate and measuring plate containing 100 openings, thereby

limiting the loading capacity to 100 initiators per cycle. A plate of this capacity need be only seven inches in length and width. Obviously, it is entirely feasible to use larger plates having more openings if desired.

The measuring plate may be removed very simply and replaced with one having smaller or larger openings. This permits accurate regulation of the quantity of ignition powder per unit charge, and the apparatus can thus be rapidly adjusted to meet changing specification of loading. There are a minimum amount of moving parts contacted by the sensitive explosive composition, thus reducing the hazard of explosion. Only a small quantity of the explosive is present in the apparatus at any one time, so that the force of any accidental detonation would be relatively slight. The explosive is not under confinement, and any detonation would cause only slight damage, if any.

The described machine is very easy to clean. By mechanism not shown, the crosshead 27 is tilted up so as to lift the paddles out of hopper 1. By actuation of hydraulic unit 23, the rack-bar 4 is moved downwardly, thus rotating base plate 2. Before pin 55 becomes disengaged from yoke 21, cam-roller 56 enters the cam-track 57 in housing 11, and the yoke 21 is thus prevented from lateral movement during the dumping operation. By this action, the sealing elements 38 are maintained in contact with the openings 36, and powder in the hopper 1 cannot pass through the openings. A tub or similar receptacle can be provided to catch the powder being dumped as the tub 1 is inverted, and substantially all of the powder will thus be removed. It is then possible to complete the cleaning and changing of the plates, etc., without danger. To restore the machine to its operating position, the rack-bar 4 is raised by the hydraulic unit 23 until the base-plate 2 rests on the pins 13, and the paddle assembly is returned to its initial position.

While the present invention has been described in considerable detail with reference to the particular embodiment shown, it will be understood

45

that many variations may be made. The arrangement of the paddle drive, for example, may be replaced with any conventional arrangement for accomplishing the desired movement of the paddle blades. We intend, therefore, to be limited only by the following claims.

We claim:

1. In an apparatus for loading explosive charges into initiator shells, the combination comprising a hopper, a flat base plate in the lower portion of said hopper, said base plate containing a plurality of apertures perpendicular to the surface thereof and of equal size, a nozzle-plate beneath said base plate, said nozzle-plate containing downwardly projecting nozzles and upwardly projecting mushroom-shaped sealing elements in axial alignment with said apertures in the base plate, said sealing members having a head of larger diameter than the diameter of said aperture, and openings in the base communicating with said nozzles, means for depositing explosive composition into each of said apertures, and means for vertically reciprocating said nozzle-plate.
2. In an apparatus as claimed in claim 1, the combination wherein the sealing elements are of a rubber-like resilient material.
3. In an apparatus as claimed in claim 1, the combination wherein the depositing means comprises a paddle mechanism.
4. In an apparatus as claimed in claim 1, the combination wherein the depositing means comprises a two-bladed paddle mounted on a shaft capable of being rotated and of being moved horizontally, one of said blades reaching to a point above the surface of said base plate and the other blade reaching to the surface of said base plate.
5. An apparatus as claimed in claim 1, wherein said hopper is pivotably mounted and mechanical means are provided for inverting said hopper.

CHARLES RUSSELL JOHNSON.
EDGAR H. SCHMIDT.
